UNITED STATES PATENT OFFICE.

HENRY T. DOULETT, OF BROCKTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

ART OF SHOEMAKING.

Original application filed November 13, 1914, Serial No. 871,990. Patent No. 1,434,356, dated October 31, 1922. Divided and this application filed March 1, 1915. Serial No. 11,201.

To all whom it may concern:

Be it known that I, HENRY T. DOULETT, a citizen of the United States, residing at Brockton, in the county of Plymouth and 5 State of Massachusetts, have invented certain Improvements in the Art of Shoemaking, of which the following description, in connection with the accompanying drawings, is a specification, like reference characters 10 on the drawings indicating like parts in the several figures.

This invention relates to methods of inserting eyelets, and is herein set forth by way of illustration in its application to the 15 setting of eyelets in such manner that the ends of the eyelet barrels are clenched between adjacent layers of material. When eyelets are so inserted in boots or shoes, the operation is known as blind or invisible eye- 20 letting. It is characteristic of both of these operations that the eyelet is inserted through one or more of the layers of the shoe upper from the side opposite to that from which 25 the eyelet setting tool enters, and that the end of the eyelet barrel is clenched between adjacent layers of the upper.

The terms "blind eyeleting" and "invisible eyeleting" have frequently been used 30 interchangeably. Strictly speaking, however, in blind eyeleting the eyelet is inserted through the outer layer, that is, the upper leather, and set with its flange or head seated upon the outside of the upper leather, so that the eyelet flange is visible on the exterior of the finished shoe, the end of the 35 eyelet barrel being clenched between adjacent layers of the upper, usually between a reinforcing stay and a lining or facing. In invisible eyeleting, as distinguished from blind eyeleting, the eyelet is 40 inserted in the inner layer, that is, the lining or facing, and set with its flange seated upon that layer, the end of the eyelet barrel being clenched between 45 the upper leather and the adjacent layer, which is usually the reinforcing stay, so that the eyelet is not visible on the exterior of the shoe.

The invention will be set forth herein 50 with particular reference to its applicability to the insertion of invisible eyelets in boots and shoes, although it is to be understood

that in various aspects the invention is not so limited.

Prior to the present invention, the setting 55 of eyelets invisibly in boots and shoes was an inconvenient, slow and expensive operation. Before this invention, invisible eyeleting was generally performed in one of two ways. Some manufacturers inserted invisible eyelets before the layers of the upper were stitched along the lacing slit and around the top of the upper, the layers being partly secured together by cement or by stitching in such manner as to leave them 60 unsecured at their edges adjacent to the lacing slit. Then, after all the lacing holes had been punched through all the layers of the upper, the margin of the outer or leather layer along the lacing slit was turned back 65 from the inner layers so that the eyelets could be set in the inner layers in the regular way, that is, as visible eyelets are set. Other manufacturers completely stitched the 70 layers of the upper together along the lacing slit and around the top of the upper before inserting the eyelets, punched all the lacing holes through all the layers, and then turned the outer or leather layer of the upper back away from the inner layers 75 and set the eyelets in the inner layers in the regular way.

Both of these practices were open to serious objections. In the first place each 80 of these practices required that the punching of the lacing holes and the setting of the eyelets be performed by the use of different machines in two separate operations and was, therefore, slow and expensive. Moreover, the first of these practices not only involved additional handling of the upper in 85 order to complete the stitching, but it frequently happened that, by reason of the parting of the edges of the upper to permit the setting of the eyelets, the layers of the 90 upper became disarranged so that the eyelets failed to register properly with the lacing holes in the finished shoe. When the second practice above outlined was followed, it was awkward and difficult to insert the 95 topmost eyelets, even when the outer or upper leather layer has been turned back 100 away from the other layers as far as possible, because of the proximity of the lacing

holes at the top of the shoe to the corners formed by the stitched edges of the upper. Furthermore, the insertion of the topmost eyelets frequently involved unavoidable dis- 5 torsion of the layers relatively to each other and in this event also the eyelets failed properly to register with the lacing holes.

In setting eyelets in accordance with the novel method of this invention, after the 10 layers of the material have been assembled in the relation which they are to have in the finished shoe, a setting tool is inserted in a hole in the material and, during relative movement of the setting tool and the eyelet, 15 the end of the eyelet barrel is turned outward and downward while the upsetting shoulder of the tool is located in its operative position between two adjacent layers of the material. In the exemplification of 20 the method herein set forth with particular reference to its application to setting invisible eyelets in the manufacture of shoes, an eyelet setting tool is inserted in a lacing hole through the layers of a shoe upper from 25 one side of the upper, and an eyelet is advanced into engagement with the other side of the upper in alinement with the setting tool. The eyelet and the setting tool are then relatively moved to force the end of the 30 eyelet barrel through one or more layers of the upper into engagement with the upsetting shoulder of the tool between the outer or leather layer of the upper and the adjacent layer, usually and as herein illustrated 35 a reinforcing stay. During continued relative movement of the setting tool and the eyelet, the setting shoulder of the tool curls the end of the eyelet barrel progressively outward and downward so as to clench it 40 upon the reinforcing stay beneath the upper leather.

In eyelet setting tools as heretofore constructed it has been considered necessary to form the upsetting surface in such manner 45 as to shape completely the clenched end of the eyelet barrel. In case the usual convex clenching is desired the upsetting surface is made substantially semi-circular in cross-section, the semi-circular contour being more 50 or less flattened in accordance with the requirements of the work but in all cases being shaped to engage the clenched portion of the eyelet barrel out to its outer edge. I have discovered, however, that satisfactory clenching 55 may be produced by the employment of an upsetting surface which in cross section or contour comprises an arc of not more than 90° and which will not engage the clenched portion of the eyelet barrel over its whole 60 width but will act to impart a partial curl or roll to so much of the end of the eyelet barrel as is forced over it. As the clenching operation progresses the material of the eyelet barrel, which is inherently ductile, will 65 follow along the same curved path that has

been imparted to its advancing end, first outward and then downward into engagement with the surface of the work. In this way there is formed in the barrel a complete clench of substantially semi-circular cross 70 section. This discovery is of the greatest importance in connection with invisible eyeletting since it renders it possible for the first time to utilize for this work an upsetting tool introduced through a small hole in the 75 outer layer of the work. Moreover the novel procedure of imparting an initial outward curl to the eyelet barrel and then progressively subjecting more of the barrel to the same treatment as the ends of the eyelet 80 prongs pass beyond the setting shoulder is itself of great importance.

The practice of the method of this invention has overcome the above-mentioned and other difficulties previously encountered in 85 blind and invisible eyeletting, since this invention makes it entirely practicable to punch lacing holes and set the eyelets in shoe uppers with the ends of the eyelet barrels clenched between adjacent layers of the 90 upper all in one operation and with substantially the same ease and facility as the setting of regular visible eyelets. The present invention also makes it entirely practicable for the layers of shoe uppers which are to 95 have blind or invisible eyelets inserted in them to be permanently and completely secured together before the eyeletting in the relation which they are to have in the finished shoe, so that the uppers may be han- 100 dled in the factory in the usual routine and with the usual sequence of operations. Moreover, blind or invisible eyelets may be inserted in shoe uppers without disturbing in the slightest the normal and final relative 105 positions of the layers of the uppers, thus insuring perfect alinement of the eyelets with the lacing holes.

Referring to the accompanying drawings which exemplify the practice of the present 110 invention in a preferred manner:

Fig. 1 is a view illustrating the step of securing together the edges of the layers of material of a shoe upper;

Fig. 2 is a perspective view, partly broken away, of a shoe upper having invisible eyelets inserted therein, with a setting tool and punch in operative relation thereto;

Figs. 3 and 4 are large scale views further illustrating the operation of inserting an invisible eyelet in the layers of material of a shoe upper; and

Fig. 5 is a longitudinal section of the setting tool of Figs. 2, 3 and 4.

When eyelets are to be set in shoe uppers 125 in accordance with the novel method of this invention as exemplified in the drawings, preparatory to the insertion of the eyelets the outer or leather part of the shoe upper and the lining part are stitched together at 130

their edges along the lacing slit 11 and approximately at right angles thereto around the top 13 of the upper, the layers of the upper, comprising the upper layer 10, 5 the lining 12 and the reinforcing stay 14, having been previously cemented together. Also, usually simultaneously with the stitching, the surplus lining material is trimmed off. This operation, termed "under trimming," is illustrated in Fig. 1 in which the needle bar 16 of a sewing machine is shown with a needle 18 and a cutter 20 secured thereto, the cutter 20 operating progressively as the stitching proceeds along 10 the edge of the upper. By this procedure the layers of the shoe upper are permanently secured together in the relation which they are to have in the finished shoe and the upper is ready to be eyeleted.

20 In setting eyelets invisibly in shoes, as herein illustrated, a setting tool 26 is inserted from the outer side of the layers of a shoe upper by introducing the leading end 24 of the setting tool 26 through a lacing 25 hole 23 in the shoe upper, the hole 23 having been punched through the layers of the shoe upper by a punch 22.

An eyelet 28 is introduced from the opposite side of the upper; that is, as illustrated, it is advanced into engagement with the lining 12, the eyelet being supported upon a lower set 30 having a center spindle 32 by which the eyelet is taken from a race-way (not shown) and which is forced back 35 into the lower set 30 when the spindle 32 engages the leading end 24 of the setting tool 26. The lower set 30 is raised to cause relative movement of the setting tool 26 and the eyelet 28 to force the end 33 of the eyelet barrel through the lining 12 and the reinforcing stay 14 into engagement with the upsetting shoulder 34 of the setting tool 26 which shoulder is then located between the outer or leather layer 10 and the reinforcing 40 stay 14 as illustrated in Fig. 3.

During further relative movement of the upper and lower sets the prongs 35 of the eyelet barrel are forced outwardly and then downwardly between the outer layer 10 and 50 the reinforcing stay 14 and clenched upon the reinforcing stay 14 as illustrated in Fig. 4.

It will be observed that the upsetting shoulder 34 of the setting tool 26 is formed 55 with a curvature of 90° or thereabouts (in cross section) so that it does not at any time engage the clenched portion of the eyelet barrel over its entire extent. During the relative movement of the eyelet 28 and the setting tool 26, as the eyelet prongs are progressively subjected to the action of the upsetting shoulder 34 of the tool, the upsetting shoulder acts upon successive portions 60 of the eyelet prongs back of their ends, thus progressively continuing the curling action

of the prongs and causing the ends of the prongs, as they pass beyond the upsetting shoulder, to maintain the curvature initially imparted to them by the upsetting shoulder and causing them to curl outwardly and 70 downwardly until the prongs are eventually clenched upon the reinforcing stay 14.

It will also be observed that the curvature of the upsetting shoulder 34 of the setting tool 26 provides an upsetting surface of 75 relatively small diameter. This restricted upsetting shoulder is adapted to be inserted through even the small lacing holes usually provided in shoe uppers which are to be invisibly eyeleted. Moreover, the setting tool 80 which is initially passed through all the layers of the material is not withdrawn from any of the layers until after the completion of the eyelet setting operation so that it ensures that the holes in both the 85 leather and lining parts of the upper are positively held in alignment with each other.

The successive eyelets are set one after another in the manner above described until 90 the row of eyelets is completed.

The relative movements and manipulations of the eyelets, the work, and the setting tool required for inserting invisible eyelets in shoes in accordance with this novel 95 method may be carried out by a machine having a general organization such as that illustrated in United States Letters Patent No. 603,023, granted April 26, 1898 on application of Seymour Field. The eyelet-setting device herein illustrated is described and claimed in United States Letters Patent No. 1,434,356, granted October 31, 1922, this application being a division of the application upon which that patent was granted. 100

The illustrated eyelet-setting tool is provided with a shank 36 threaded into a sleeve 38, a lock screw 40 maintaining the shank 36 in adjusted position in the sleeve 38 (see Fig. 5). Surrounding the lower end of the 110 sleeve 38 is a sliding sleeve 42, the lower end 44 of which serves as an abutment to limit the movement of the upper leather 10 past the upsetting shoulder 34. Movement of the sliding sleeve 42 lengthwise of sleeve 38 is 115 limited by a screw 46 threaded into sleeve 38 and passing through a slot 48 formed in sliding sleeve 42. A coiled spring 50 surrounding the shank of the setting tool and housed in sliding sleeve 42 normally tends to maintain the sliding sleeve 42 at the lower limit of its path of movement but permits that sleeve to rise if necessary to permit the passage of the upper leather 10 past the upsetting shoulder 34, at the same time pressing the 120 upper leather against the eyelet and tending to flatten the curled ends of the eyelet prongs at the conclusion of the clenching operation. The illustrated setting tool 26, like the setting tool illustrated in said Letters Patent No. 130

1,434,356, is formed with a contracted portion or recess 52 above its upsetting shoulder 34.

The novel method of the present invention is not limited to the use of a machine having a separate punch and set nor is it dependent upon the use of any particular apparatus. It should be noted, moreover, that in many of its aspects the invention is not limited to the setting of invisible eyelets and the claims should not be so construed except so far as their terms may require.

Having thus described my invention, what I claim as new and desire to secure by Letters Patent of the United States is:—

1. In the manufacture of boots and shoes, that method which consists in permanently securing together the leather and lining parts of an upper in the relation which they are to have in the finished shoe, punching a hole through both parts, passing an upsetting surface through the hole in the leather part to locate it between the two parts and inserting the barrel of an eyelet through the lining part, and finally clenching the eyelet barrel against the upsetting surface and upon the lining part.

2. In the manufacture of boots and shoes, that method which consists in securing together the leather and lining parts of an upper by stitching through both parts along the lacing slit edges and at approximately right angles thereto around the top of the upper, punching an eyelet hole through both parts within the stitched edge, introducing an upsetting surface between the parts, and clenching the end of an eyelet barrel between adjacent surfaces of the parts of the upper while the parts remain in normal relation.

3. In the manufacture of boots and shoes, that method which consists in stitching and undertrimming the forward or lacing slit edges of an upper, punching both the leather and lining parts, and introducing an upsetting surface between the parts through the leather part and forcing an eyelet through the lining part and against the upsetting surface until the end of its barrel is clenched on the surface of the lining part which is adjacent to the leather part.

4. The improved method of inserting eyelets in a plurality of layers of material which comprises inserting a setting tool through the layers from one side of the material, advancing an eyelet into engagement with the other side of the material, relatively moving the eyelet and the setting tool to force the end of the eyelet barrel through one or more of the layers into engagement with the upsetting shoulder of the tool between adjacent layers of the material, and continuing said relative movement of the setting tool and the eyelet to clench the eyelet barrel between said adjacent layers.

5. That improvement in methods of inserting eyelets in a plurality of layers of material and clenching the ends of the eyelets between adjacent layers of the material, which is characterized by the fact that a setting tool is inserted through a hole in the outer layer and, during relative movement of the setting tool and an eyelet, the end of the eyelet barrel is turned over and clenched by the setting shoulder of the tool between adjacent layers of the material.

6. In the manufacture of boots and shoes the herein-described method of setting blind or invisible eyelets consisting in securing together permanently in normal relation the leather and lining parts of a shoe upper by stitching the edges of said upper adjacent to the lacing slit, and perforating both parts and setting an eyelet in one part in register with the hole in the other part while the two parts are permanently secured together and maintained in their normal relation to each other.

7. In the manufacture of boots and shoes the method of setting blind or invisible eyelets consisting in securing together permanently in normal relation the leather and lining parts of a shoe upper, the entire edges of the two parts being permanently fastened together by stitching or otherwise, and perforating both parts and setting an eyelet in one part in register with the hole in the other part while the two parts are permanently secured together and the holes in both parts are positively held in alignment with each other.

8. That improvement in methods of inserting eyelets in a plurality of layers of material which comprises inserting on one side of the layers of material a setting tool having an upsetting surface of relatively small diameter, advancing an eyelet into engagement with the other side of the material, relatively moving the eyelet and the setting tool to force the eyelet barrel through one or more layers of the material in the hole in the material through which the setting tool passes into engagement with the upsetting surface of the tool between adjacent layers of the material, thereby imparting an initial outward curl to the ends of the eyelet prongs, and continuing the relative movement to bring successive portions of the eyelet barrel back of the ends of the eyelet prongs progressively into engagement with the upsetting surface, thereby causing the ends of the prongs as they pass beyond the upsetting surface to maintain the curvature initially imparted to them by said surface and causing them to curl outward and downward between the adjacent layers of the material until the prongs are clenched upon the lower of said adjacent layers.

9. In the manufacture of boots and shoes

- the improved method which consists in permanently stitching together the leather and lining parts of an upper in the relation which they are to have in the finished shoe 5 by stitching the edges of said parts together along the lacing slit and around the top of the upper, inserting on one side of the upper a setting tool having an upsetting surface of relatively small diameter, advancing an eyelet into engagement with the other side of the upper, relatively moving the eyelet and the setting tool to bring the end of the eyelet barrel into engagement with the upsetting surface of the tool between adjacent layers of the material to 10 impart an initial outward curl to the ends of the eyelet prongs, and continuing the relative movement to bring successive portions of the eyelet barrel back of the ends of the eyelet prongs progressively into engagement with the upsetting surface, thereby controlling the curvature of the eyelet prongs as they pass beyond the upsetting surface and causing them to curl outward and downward between the adjacent layers 15 of the material until the prongs are clenched upon the lower of said adjacent layers.
- In testimony whereof I have signed my name to this specification in the presence of two subscribing witnesses.

HENRY T. DOULETT.
